PROPELLER

Guy S. Faber, Chicago, Ill., assignor to General
Regulator Corporation, Chicago, Ill., a corpora-
tion of Illinois

Application August 8, 1930, Serial No. 473,988

15 Claims. (Cl. 170—172)

My invention relates to propellers formed of blades radiating from the axis of the device, as for example in the case of fans for creating a flow of air, or agitators.

My object generally stated is to provide a construction of propeller which will operate with greater efficiency than devices as hitherto provided to the end that a propeller of given size will exert a much greater propelling force than heretofore, and in the case more particularly of its use as an air fan, will produce a greater flow of air than in the use of structures as hitherto provided; thereby permitting of the use of a propeller of smaller size and operated by a power device consuming less energy than in the case of prior structures.

Referring to the accompanying drawing:

Figure 1 is a face view of one form of propeller constructed in accordance with my invention.

Figure 2 is an edge view of the same.

Figure 3 is an enlarged sectional view taken through one of the similar blades of the propeller, the section being taken at the line 3 on Fig. 1 and viewed in the direction of the arrow; and

Figure 4, a view like Fig. 3 of a modified form of the invention.

Referring to the particular embodiment of my invention illustrated in Figs. 1, 2 and 3, the propeller shown is of the substantially radial four-bladed type, though the invention may be embodied in a propeller the number of blades of which is greater or less than shown.

The blades 4 of the propeller are inclined, or pitched, at an angle to their plane of rotation in the usual manner. The shaft by which the propeller is driven is represented at 5 and the blades extend outwardly at right angles to the shaft as shown in Fig. 2. As shown in Fig. 1 the major portion of each blade and the slot therein lies to the rear of the direction of rotation of the line radial to the shaft axis which is common to the two opposite blades.

Each blade 4 preferably, and as shown, slightly tapers from its end adjacent the center of the propeller to its outer extremity as shown, the taper being such that the propelling action of the blade throughout substantially its entire length is substantially uniformly effective, whereby the fluid being operated on by the propeller is forced therefrom in a substantially solid column in which the fluid throughout its cross section moves at substantially the same velocity.

In this connection it will be noted that the speed of travel of the propeller at the outer extremities of its blades is the maximum and gradually decreases toward the inner ends of the blades. Thus by tapering the blades as stated provision is made for compensating for the condition above mentioned and thus effecting the discharge by the propeller of a substantially solid, uniform flow, column of fluid as above stated.

According to my invention the blades 4 contain slots 6 shown as extending generally lengthwise thereof and are provided with deflecting surfaces so disposed that the fluid displaced by the blades is deflected more or less sharply in a forward direction adjacent the slots 6 to create suction action at the slots. These deflecting surfaces represented at 7 and 8 are preferably formed by deflecting forwardly the metal at those edges of the slots 6 which are the forward ones of their opposite edges considering the direction of rotation of the fan as represented by the arrow 8^a in Figs. 1 and 2 and the metal beyond these slots the forward faces of the deflected portions 7 and 8 preferably being of curved shape as shown.

The result of providing the slots 6 as stated and the deflecting surfaces 7 and 8 is to cause a great degree of suction to be produced at the slots which action on the fluid at the rear of the fan produces a marked flow of fluid from the rear to the front of the fan through the openings in the blades.

Each deflecting surface 7 and 8 functions in the production of the suction action at the slots 6 and while each blade is preferably provided with both surfaces 7 and 8 as stated, I do not wish to be understood as intending to limit my invention thereto as either one of these deflecting surfaces may be dispensed with, but with accompanying decrease in the efficiency of the device without departing from my invention.

Under some conditions it may be desirable to provide each blade with a plurality of slots extending generally lengthwise of the blade preferably substantially the entire length thereof as in the case of the slots 6 and in more or less parallel relation to each other. In Fig. 4 I have illustrated, by a cross-sectional view, a blade having two such slots represented at 9 and 10, though it will be understood that the number thereof may be increased if desired, with a forwardly extending curved deflecting surface 11 extending substantially entirely along the advance edge of the slot 9; a substantially similar

deflecting surface 12 at the advance edge of slot 10 and to the rear of the slot 9 and a substantially similar deflecting surface 13 at the rear of the slot 10, whereby suction action is exerted 5 at each of the slots 9 and 10.

As to this construction it is within my invention to eliminate either or both of the surfaces 11 and 13, inasmuch as the construction thus modified would produce suction through the 10 openings 9 and 10 but to a less degree than in the case of the use of either or both of the surfaces 11 and 13.

While I have illustrated and described certain particular embodiments of my invention, I 15 do not wish to be understood as intending to limit it thereto as the same may be variously modified and altered without departing from the spirit of my invention.

What I claim as new, and desire to secure by 20 Letters Patent, is:

1. A propeller the blades of which contain 25 openings therethrough, each of said blades having a forwardly-extending, deflector surface adjacent an edge of the opening therein operative to produce suction at said opening.

2. A propeller the blades of which contain 30 openings therethrough, each of said blades having a forwardly-extending, deflector surface adjacent the advance edge of the opening therein and operative to produce suction at said opening.

3. A propeller the blades of which contain 35 openings therethrough, each of said blades having a forwardly-extending, deflector surface extending in front of and beyond the opening therein operative to produce suction at said opening.

4. A propeller the blades of which contain 40 openings therethrough, each of said blades having a forwardly extending curved deflector surface adjacent an edge of the opening therein operative to produce suction at said opening.

5. A propeller the blades of which contain 45 openings therethrough, each of said blades having a forwardly extending curved deflector surface adjacent the advance edge of the opening therein operative to produce suction at said opening.

6. A propeller the blades of which containing 50 openings therethrough, each of said blades having a forwardly extending curved deflector surface extending in front of and beyond the opening therein operative to produce suction at said opening.

7. A propeller the blades of which contain 55 openings therethrough, each of said blades having forwardly extending deflector surfaces located at opposite sides of the plane of the opening therein operative to produce suction at said opening.

8. A propeller the blades of which contain 60 openings therethrough, each of said blades having forwardly extending curved deflector sur-

faces located at opposite sides of the plane of the opening therein operative to produce suction at said opening.

9. A propeller the blades of which contain 5 openings therethrough, each of said blades having a forwardly-extending deflector surface adjacent the advance edge of the opening therein and extending forwardly beyond the rear edge of the opening and operative to produce suction at said opening.

10. A propeller the blades of which contain 10 slots extending lengthwise thereof, said slots being located closer to the trailing edges of the blades than to their leading edges and said blades being so shaped as to create suction 15 toward the rear of the propeller through said slots in the rotation of the propeller.

11. A propeller the blades of which contain 20 openings therethrough, said blades having forwardly-extending deflector surfaces adjacent the leading edges of said openings operative to produce suction at said openings, the major portions of said blades and the openings therein lying to the rear of the direction of rotation of the line radial to the shaft axis which is common to the 25 opposite blades, said blades being so shaped as to create suction toward the rear of the propeller through said openings in the rotation of the propeller.

12. A propeller each blade of which contains 30 a plurality of openings therethrough disposed in different positions in a direction crosswise of the blade, said blades having forwardly extending 35 deflector surfaces adjacent the leading edges of said openings and operative to produce suction at said openings.

13. A propeller the blades of which contain 40 slots extending lengthwise of the blades but to the rear of the direction of rotation of the line radial to the shaft axis which is common to the 45 two opposite blades, said blades having forwardly extending deflector surfaces adjacent the leading edges of said slots operative to produce suction at said slots.

14. A propeller the blades of which contain 50 slots extending lengthwise of the blades but to the rear of the direction of rotation of the line radial to the shaft axis which is common to the two opposite blades and substantially parallel with said axis, said blades having forwardly extending deflector surfaces adjacent the leading edges of said slots operative to produce suction at said slots.

15. A propeller the blades of which contain 55 slots extending lengthwise thereof, said blades being of decreasing widths from points adjacent their bases toward their outer ends and having forwardly extending deflector surfaces adjacent the leading edges of said slots operative to produce suction at said slots.
